UNITED STATES PATENT OFFICE.

ALBERT C. VAN ERKA, OF CHICAGO, ILLINOIS.

WINDOW-SHADE CARRIER.

No. 901,398.

Specification of Letters Patent.

Patented Oct. 20, 1908.

Application filed December 23, 1907. Serial No. 407,647.

To all whom it may concern:

Be it known that I, ALBERT C. VAN ERKA, a citizen of the United States, residing at Chicago, in the county of Cook and State 5 of Illinois, have invented certain new and useful Improvements in Window-Shade Carriers, of which the following is a specification.

This invention relates to window-shade carriers, and more particularly a device whereby the shade may be raised or lowered bodily and set at any desired point on the window-casing, the object being to permit light and air to enter at the top of the 15 window above the shade.

The invention comprises a carrier of improved construction, together with means for operating the same as will be fully described hereinafter.

20 In the accompanying drawing, Figure 1 is an elevation of the invention, parts being shown in section. Fig. 2 is a section on the line 2—2 of Fig. 1.

Referring specifically to the drawing, 5 denotes a channeled plate secured to one side of the window-casing and having at one edge an overhanging flange 6 in the edge of which is a rack 7. The opposite side of the window-casing is provided with a corresponding channeled plate 5^a having a rack 7^a. These guide-plates extend vertically on opposite sides of the window-casing and serve to guide and retain the shade-roller carriers and devices to be hereinafter 30 described, the racks 7 and 7^a being engaged by pinions carried by the roller. One of the carriers is a plate 8 which is slidably mounted in the channel 5 and on the face of the plate is pivoted at 9 a plate 10 having a projection 11 which is engageable with the rack 7. The plate also has teeth 12 in its edge which mesh with teeth 13 in the edge of a disk 14 pivoted at 15 on the face of the plate 8. The disk 14 also has a projection 16 engageable with the rack 7.

To the upper end of the plate 8 is fastened a laterally extending arm 17 and on the plate 10 is a laterally extending arm 18. To these arms are made fast the respective ends of a 50 cord 19 which passes over pulleys 20 and 20^a secured in frames 21 mounted on the window-casing. The pulley 20 is located above the arm 17, and the pulley 20^a is below the arm 18. The projections 11 and 16 are nor-

mally held in engagement with the rack 7 by 55 means of a spring 22 secured at 23 to the plate 8 and pressing with its free end on a pin 24 projecting from the plate 10.

In the plate 8 is journaled one end of the spindle 25 of the shade-roller, and outside 60 the latter a pinion 26 is fixed on the spindle. This pinion travels on the rack 7 and has shroud-plates 27 which serve to hold the pinion in proper position and in engagement with the rack. On the shade-roller spindle 65 is also secured a sleeve 28 having ratchet teeth 29 engageable by pawls 30 mounted on the ring-plate 31 at the end of the tubular roller 32 to which the cloth shade will be fastened. A spring (not shown) is provided to 70 operate the roller in a well known manner. At the opposite end of the roller the spindle has a shrouded pinion 33 which travels on the rack 7^a, and on the spindle is also mounted a roller 34 which travels on the 75 flange of the plate 5^a and holds the pinion in engagement with the rack 7^a. The shade-roller spindle is in two sections connected by a slide-coupling 35 which allows longitudinal adjustment to bring the pinions 26 and 80 33 into proper engagement with the racks.

When the projections 11 and 16 are in engagement with the rack, the carrier plate 8 is locked in the channel 5. To release the plate the arm 18 is pulled downwardly by 85 means of that end of the cord 19 which is attached thereto, which swings the plate 10 on its pivot and withdraws the projection 11 from the rack 7. At the same time, by reason of the gearing between the plate 10 and 90 the disk 14 the latter also turns on its pivot whereby the projection 16 is also withdrawn from the rack 7. This releases the carrier plate 8 and permits it to be moved up and down in the channel 5. Upon releasing the 95 cord 19 the spring 22 turns the plate 10 in the direction to reengage the projections 11 and 16 with the rack, whereby the plate 8 is locked in the channel 5.

I claim:—

1. A shade-roller fixture comprising opposite guides and racks, a slide mounted in one of the guides, a shade-roller spindle journaled at one end in the slide, pinions on opposite ends of the spindle which engage the 105 racks, a pair of operatively connected rack-catches on the slide, and means for operating the catches.

100

- 12
- 2. A shade-roller fixture comprising opposite guides and racks, a slide mounted in one of the guides, a shade-roller spindle journaled at one end in the slide, pinions on opposite ends of the spindle which engage the racks, a rack-catch carried by the slide, and an operating-cord connected at one end to the slide for elevating the same, and at the

other end to the catch for simultaneously releasing the same and lowering the slide. 10

In testimony whereof I affix my signature, in presence of two witnesses.

ALBERT C. VAN ERKA.
